UNITED STATES PATENT OFFICE.

JOHN J. NEWMAN AND LLOYD L. NEWMAN, OF ROCKWOOD, PENNSYLVANIA.

NEWSPAPER CLAMP.

Application filed June 24, 1922. Serial No. 570,715.

To all whom it may concern:

Be it known that we, JOHN J. NEWMAN and LLOYD L. NEWMAN, citizens of the United States, residing at Rockwood, in the county of Somerset and State of Pennsylvania, have invented certain new and useful Improvements in Newspaper Clamps, of which the following is a specification.

The present invention relates to improvements in paper clamps and has for an object to provide a simple and inexpensive device adapted for attachment to newspapers, blue prints, specifications and other papers or the like in which numbers of sheets are to be held securely together against accidental detachment and for ready folding so as to give access to inner sheets without creasing at the fold.

Other objects of the invention are to provide a device for the above purpose in which the article may be stamped conveniently and quickly from spring metal or other appropriate material and bent to shape in two operations; wherein the device is so constructed and shaped as to permit of being readily attached to a sheaf of papers and having a resilient binding engagement therewith such as to oppose successfully any tendency to pull the clamp from the papers in any other direction than a longitudinal movement coinciding with the edges of the paper sheets.

With the foregoing and other objects in view, the invention will be described more particularly in the following description and will be set forth in detail in the appended claims.

In the drawings, wherein like numerals refer to like or corresponding parts through the several views,

Figure 1 is a plan view of a newspaper showing applied thereto an improved clamp constructed according to the present invention.

Figure 2 is a transverse sectional view taken through the clamp and through a number of sheets of papers held thereby, and showing one method of folding the sheets upon the clamp.

Figure 3 is a plan view of the improved clamp.

Figure 4 is a longitudinal section taken on the line 4—4 in Figure 2. Figure 5 is an end view of the device, and

Figure 6 is a side view with a central por-

tion broken away showing a suspending ring.

Referring more particularly to the drawings the improved clamp consists of a piece of sheet material rolled substantially into a cylinder 7 having its longitudinal free edges 8 and 9 slightly overlapped.

The material of which the clamp is made is preferably thin resilient steel although other metal or material may be found well suited to the purpose, particularly celluloid. The end portions of the cylinder 7 are mutually curved as represented at 10 and 11, inclining toward the overlapped parts 8 and 9 and forming jaws to guide the edges of the paper into the clamp. Moreover as most clearly shown in Figures 4 and 6 the end portions of the cylinder are drawn outwardly or flared as at 12 to avoid coming in contact with the paper or cutting or doing other injury thereto.

In Figure 6 we have illustrated the device as equipped with a ring or eye 13 split as at 14 and inserted through openings 15 and 16 made in the central upper portion of the clamp cylinder. The ring affords an excellent means for suspending the clamp upon a nail or hook extending from a wall and in this connection the device will be found appropriate for the holding of calendar sheets.

In Figure 1 the improved clamp is shown in place upon the newspaper 17. The clamp will normally occupy a position substantially centrally of the sheet and in this position it will reinforce and back the pages of the paper thereby enabling the reader to fold the sheets backwardly upon themselves giving access to the interior of the paper without encountering crinkling of the sheets along the fold line. This difficulty is found particularly in railway trains or in other windy places. We have also indicated in dotted lines in Figure 1 the clamp as having been moved to a lower position upon the paper, this to enable the newspaper to be folded upon the transverse line 18. The paper may thus be folded or rolled up and placed in the pocket without having to entirely detach the clamp therefrom. However, if desired the clamp may be removed and placed in the pocket. It will not be inconvenient nor troublesome to carry any more so than a lead pencil or fountain pen.

As the clamp is slipped over the edges of the sheets, due to the overlapping parts 8

110

and 9, the paper will be given a tendency to curl within the hollow cylinder and the parts 8 and 9 will be pried apart slightly, creating pressure upon the sheets due to the elasticity inherent in the metal. Furthermore the construction and disposition of the overlapped edges is such that any tendency to pull the clamp from the sheets at right angles to the edges of the sheets will develop an extremely strong resilient action in the clamp tending to bind the papers more closely therein. In this way any attempt will be successfully resisted to withdraw the clamp in any other than the longitudinal sliding movement and this will be relatively easy for the user in attaching and removing the clamp but the frictional engagement will be such as to avoid the clamp casually creeping along the edge of the paper.

It will be appreciated from the foregoing that we have provided an improved clamp suitable for binding papers of any character together and for allowing the sheets to be folded without difficulty, crinkling or creasing. The improved clamp is made from relatively inexpensive material involving in its manufacture but two operations so that the resultant product is economical and may be sold in the market at small cost.

We have shown and described a preferred and satisfactory construction but it is obvious that various changes and modifications might be made and we wish it under-

stood that we reserve the right to make all such changes as may fall within the scope of the following claims.

What is claimed is:

1. A clamp comprising a resilient sheet metal body rolled into substantially tubular form with its longitudinal edge portions slightly overlapped a distance sufficient only to bind against the opposite sides of an interposed sheet and with the inner edge of the body in biting engagement with the sheet, whereby increasing tension to withdraw the sheet is resisted by a proportionate combined resistance of the overlapping edges against circumferential as well as radial separation.

2. A clamp comprising a resilient sheet metal body rolled into substantially tubular form with its longitudinal edge portions slightly overlapped a distance sufficient only to bind against the opposite sides of an interposed sheet and with the inner edge of the body in biting engagement with the sheet, whereby increasing tension to withdraw the sheet is resisted by a proportionate combined resistance of the overlapping edges against circumferential as well as radial separation, said longitudinal edge portions being rounded off at the end of the tube body to provide a flaring mouth for the reception of the sheet, and said tube body being unobstructed on its entire exterior for folding the sheet thereabout.
